UNITED STATES PATENT OFFICE.

GUSTAV RICHARD SAGELSDORFF, OF MEDFORD, WISCONSIN.

ANIMAL-COLLAR.

SPECIFICATION forming part of Letters Patent No. 448,546, dated March 17, 1891.

Application filed October 1, 1890. Serial No. 366,729. (No model.)

To all whom it may concern:

Be it known that I, GUSTAV RICHARD SAGELSDORFF, of Medford, in the county of Taylor and State of Wisconsin, have invented 5 a new and Improved Animal-Collar, of which the following is a full, clear, and exact description.

The object of the invention is to provide a new and improved chain, which is simple and 10 durable in construction, is cheaply manufactured, and is more especially designed for use on cattle as a neckband to support a bell, the chain being adapted to be easily fastened or unfastened.

15 The invention consists of a middle piece adapted to support a bell, a series of links extending from the said middle piece, and a lock of peculiar construction for uniting the outermost links.

20 The invention also consists of certain parts and details, and combinations of the same, as will be hereinafter fully described, and then pointed out in the claims.

Reference is to be had to the accompanying 25 drawings, forming a part of this specification, in which similar letters of reference indicate corresponding parts in all the figures.

Figure 1 is a perspective view of the improvement. Fig. 2 is a similar view of one 30 end of the same, and Figs. 3 and 4 are like views of the lock in different positions.

The improved chain is provided with a middle piece A, made in U shape, as is plainly shown in Fig. 1, having fastened to 35 the middle portion thereof the eyes B, extending in opposite directions. Each of the eyes B engages a link C, made of one single piece of sheet metal of about the shape of the numeral 8, doubled up so as to form an 40 eye C', and the end C² engaging the eye B. The openings C³, between the ends and sides, reduce the weight of the link materially. Links C, of similar construction, are connected one with the other, the eye of one engaging 45 the end of the next following one, as is plainly shown in Fig. 1. The links extend in about equal numbers from the eyes B, so as to form a band of sufficient length to pass around the necks of cattle.

50 The outermost link C⁴ of one end of the chain carries a lock D, provided with a plate

E, pivoted to the eye C' of the outermost link C⁴. On the top of the plate E is erected an apertured stud F, standing at right angles to the plate E, and on which is fulcrumed the 55 hook G, provided with a hook end G'. The lower part of the stud F is formed with a reduced neck F', adapted to be engaged by the outermost link C⁵ on the other end of the chain or any other link at that end of the 60 chain. The hook end G' of the hook G is adapted to engage an ordinary link H, hung on a staple I, projecting from a plate J, riveted or otherwise fastened in the outermost link C⁴, previously mentioned. 65

The middle piece A supports between its ends a pin K, on which is hung a hook L, adapted to support in its hook end L' a cow-bell or other article, and when said bell is in place the hook L' is locked thereon by a 70 ring L², passing through the end of the hook L' and the main part of the hook L, which are apertured for this purpose.

The chain, as is shown in Fig. 1, is in an open position, and when the operator desires 75 to close the same after passing the chain around the animal's neck he first passes the hook end G' through the openings C³ of the respective link to be engaged on the other end of the chain, and then turns the lock D 80 at right angles to the links C⁵, so as to pass the stud F through the opening C³ of the said link until the latter rests on top of the plate E. The plate E is then turned back in its former position, the sides of the engaged 85 link passing under the shoulders formed by the neck of the stud F, so that the latter is locked in place on the engaged link. The hook G is now on the top of the chain and by its spring end G' is engaged with the link 90 H, so that the ends of the chain are locked together, as is plainly illustrated in Fig. 4.

In order to unlock the chain the operator proceeds by first unhooking the hook G' from the link H, then giving the plate E a quarter-turn, so that the stud F can pass through the opening C³ of the engaged link, after which the plate E is turned into its former position to permit the hook end G' of the hook G to pass through the said opening C³ of the link. 95 It is understood that by engaging the outermost link C⁵ by the lock D the chain attains 100

its largest circumference, but engaging any of the other links at that end of the chain the chain is made smaller to suit the neck of the animal on which the chain is to be applied. It will be seen that this chain can be very cheaply manufactured, is very light, and can be readily locked or unlocked on the animal's neck whenever desired.

Having thus described my invention, I claim as new and desire to secure by Letters Patent—

1. In a chain adapted to serve as an animal-collar, the combination, with two chain-sections, of the U-shaped middle piece which connects them, a pin K, supported in the outwardly-curved end of said middle piece, and

a cow-bell hook turning loosely on said pin, substantially as shown and described.

2. A chain adapted to serve as an animal-collar, the same being provided with a stud F, having a reduced neck or shank and secured to one of the terminal links and adapted to pass through the other terminal link, a hook attached to said stud, and the link II, secured to the chain contiguously to the stud, and thus adapted for engagement with the aforesaid hook to form the lock hereinbefore described.
